THERMOSENSITIVE RADIATOR CAPS
 Jesse E. Eshbaugh and John A. McDougal, Flint, Mich.,
 assignors to General Motors Corporation, Detroit,
 Mich., a corporation of Delaware
 Filed Apr. 15, 1959, Ser. No. 806,549
 4 Claims. (Cl. 236—92)

This invention relates to radiator caps and more particularly to radiator caps for pressurized engine cooling systems as utilized on automobile vehicles.

In order to prevent loss of engine coolant it is conventional to place engine cooling systems under pressure with provisions being made in the radiator filler caps for venting the systems when the coolant pressure is either too high or too low. Operating an engine under elevated but controlled coolant pressure conditions insures heat transfer efficiency, reduces the size of coolant system necessary and conserves coolant.

A conventional type radiator cap comprising a pressure relief valve and a vacuum relief valve is disclosed in the U.S. Patent No. 2,266,314 granted December 16, 1941, in the name of J. E. Eshbaugh. In such a cap, both valves are normally closed. It has been found that in caps of this type, as employed in cooling systems of internal combustion engines, the starting of a cold engine is soon followed by an expansion of the coolant and a consequent decrease in the air space of the radiator. This causes a rise of pressure long before the coolant boiling temperature is attained and this rise would occur during many short cold weather motor trips. This situation definitely increases radiator fatigue and shortens the life expectancy of the radiator.

It has now been found that the number of pressure cycles to which a radiator is subjected may be reduced appreciably and that the life of a radiator may therefore be extended with retention of the advantages of a pressurized system.

To this end, an object of the present invention is to provide an improved pressure type radiator cap which will remain vented during periods of engine warm-up and thereby minimize the number of pressure cycles to which a radiator and cooling system are subjected.

A feature of the present invention is a radiator cap having a thermostatic unit mounted outside the vapor or steam space. Another feature is a radiator cap with a thermal element loosely attached to a vacuum relief valve, the weight of the latter tending to open the valve.

These and other important features of the invention will now be described in detail in the specification and then pointed out more particularly in the appended claims.

In the drawings:

FIGURE 1 is a sectional view in elevation of a radiator filler spout assembly with a pressure type radiator cap thereon as an illustration of one embodiment of the present invention;

FIGURE 2 is a sectional view looking in the direction of the arrows 2—2 in FIGURE 1 showing a portion of the construction;

FIGURE 3 is an enlarged view of a portion of the structure shown in FIGURE 1, a vacuum relief valve being shown in its closed position; and

FIGURE 4 is a side elevation of a portion of the filler spout of FIGURE 1, the cap being shown in dot and dash lines.

In FIGURE 1, a head tank portion 10 of a radiator is shown to which is fixed a tubular filler spout 12 with an overflow or vent pipe 14 leading from the side wall of the spout to a point of discharge as is conventional. The lower end of the spout 12 has an inturned flange including an upwardly directed annular rib or valve seat 16. The lower end of the spout terminates in a depending annular

2

jar skirt 20 which extends into an opening 22 of the top wall of the radiator 10. The upper end of the spout 12 is flanged outwardly to form an annular rib 24 and a pair of dependent arcuate flanges 26 which are adapted to serve as elements of a conventional and detachable bayonet connection. These flanges are adapted to cooperate with a pair of inturned flanges 28 integral with the bottom edge of an inverted cap member generally indicated at 30.

10 A resilient metallic sealing disk 32 is provided forming a seal with the annular rib 24. The disk 32 is fixed at its center to the center of the cap 30 by a depending stud 34 which is riveted in position. A valve seating spring 36 surrounds the post 34 and the upper end of the spring seats against the underside of the diaphragm 32. At the opposite end of the spring 36 is located an annular shoulder 38 of a valve element 40. The latter has a central dome 42 which is slidably mounted on the post 34 and is provided with primary vent openings 44. The 15 lower end of the post 34 is provided with a shoulder 46 limiting the downward movement of the dome member from the stud when the cap is removed from the radiator 10. On its underside the valve element 40 carries a sealing gasket 48 which is adapted to seat on the annular rib 22. A cup-like closure member 50 is press fitted within the valve member 40 and a closure wall 52 is integral therewith. This wall bears at least one secondary vent opening 54 which is within a circle defined by a downwardly extending rib 56 formed on the wall. A relief 20 valve 60 is adapted to seat on the rib 56 or on the underside of the wall 52 to seal the vent opening or openings 54. This relief or secondary valve 60 includes a stud 62 which is slidable through the wall 52 and is fixed at its bottom end to a rigid disk 64. A sealing disk 66 is 25 confined between the disk 64 and a shoulder 68 formed on the stud 62. The upper end of the stud 62 is provided with an annular shoulder 70 in contact with a thermostatic element 72. The latter is formed of three pieces of different metal making its deflection dependent upon 30 temperature and is in the shape of a beam extending across a depressed area of the vented wall 52.

Much of the cap structure is like that described in the Patent No. 2,266,314, above referred to, but the relief valve of FIGURE 3 involves the present invention and it is to the latter structure as used in a radiator cap that the description herein is primarily limited.

It will be noted that the stud 62 is slidable through the wall 52. When the parts are positioned as shown in FIGURE 1, the valve 60 is open and the radiator head tank 10 is vented to the atmosphere by way of the overflow tube 14. Upon starting a cold engine, however, a rush of vapor through the vent openings 54 is not sufficient to lift the relief valve 60 to its closed position until the thermostatic element 72 has been affected by a sufficient elevated temperature to supplement the action of the vapor. When the thermostatic element 72 and the rush of vapor act in concert, the valve 60 will rise and the system will become pressurized with the valve 60 closed as shown in FIG. 3. If the valve 60 relied on weight alone to hold it open and on the flow of vapor alone to cause it to close, then a high rate of vapor flow would be required to close the valve and this would entail considerable loss of coolant and anti-freeze before the valve 60 would close. The thermostatic element 72 may be so calibrated that the valve 60 will close before a great 60 rush of vapor could occur during an engine warm-up period and for this reason less coolant loss results. If the thermostatic valve 60 is adjusted to close at 160° F. and the coolant cools below 212°, it would be possible to have a slight sub-atmospheric pressure in the radiator 10. The strength of the thermostatic element 72, however, 65 should be no greater than the normal vacuum relief valve

spring conventionally used and for this reason no greater vacuum could build up with the thermostatic element than is conventional.

It is obvious that the thermostatic element 72 could be made of two or three metals or could be such as to have more than two diverging branches. It will be noted that only a single beam with two ends are shown in FIGURE 2 as simplicity of structure dictates such a beam intermediately pierced by the stud 62. It is necessary that adequate clearance be left between the wall 52 and the thermostatic element 72 to delay pressure build-up by proper venting when the valve 60 is unseated from the ridge 56 or positioned as shown in FIGURE 1.

We claim:

1. A radiator cap of the pressurized type and attachable to a radiator filler spout, said cap having fixed parts including a vented valve element and a closure wall traversing said valve element and having a vent opening therein, a stud vertically slideable in said wall, a valve member carried by said stud beneath said wall, said valve member being vertically movable to seat on said wall around said opening, a thermostatic member immediately above said wall and supporting said stud on said fixed parts, and the arrangement being such that a rise in temperature plus the effect of vapor flow through said opening cooperates to effect flexure of the thermostatic member and seating of the valve member around said opening.

2. A radiator cap attachable to the filler spout of a radiator and having fixed parts including a closure wall within the cap having a vent opening therein and annular sealing means surrounding said wall, a headed stud slideable through said wall, a valve member carried by the lower end of said stud and facing the underside of said wall, said stud and valve member comprising an assembly of solid elements vertically movable to seat said valve member on said wall to close said vent opening when said assembly is subjected to a given temperature, and a thermostatic member directly above said wall operatively connected to said stud and supporting said valve member in spaced relation to said wall at a lower temperature.

3. A radiator cap attachable to the filler spout of a

radiator and including a closure wall having a vent opening therein, a stud slideable in said wall, a valve member carried by the end of said stud on one side of said wall for controlling said vent opening, a thermosensitive member resting on the other side of said wall with opposite ends only resting on said wall thereby supporting said stud and valve member and bridging said vent opening, said stud, valve member and thermosensitive member forming a solid assembly movable with respect to said wall, and said thermosensitive member being adapted to hold said valve member in a closed position with respect to said vent opening at normal operating temperature and to suspend said valve member away from said closed position at a lower temperature.

15 4. A radiator cap comprising a valve element carrying an annular sealing means adapted to engage a valve seat within a tubular filler spout serving a radiator, a primary vent opening in said valve element, a wall fixed to said valve element and traversing a space defined by said sealing means and communicating with said primary vent, a secondary vent opening in said wall, a stud slideable through said wall, a valve member and a thermostatic member connected to said stud, said valve member being movable with said stud to seat on one side of said wall 20 and close said secondary vent opening, and said thermostatic member being arranged between said primary vent opening and the other side of said wall whereby a rise in temperature plus the effect of vapor flow through said 25 secondary opening on said valve member may effect seating of the latter.
